UNITED STATES PATENT OFFICE

2,630,054

GRILLE

John E. Peterson, Downers Grove, Ill., assignor to
 Minneapolis-Honeywell Regulator Company,
 Minneapolis, Minn., a corporation of Delaware

Application March 29, 1946, Serial No. 658,311

1 Claim. (Cl. 98—40)

1

This invention relates to a grille for air conditioning systems and particularly to one which is "extended" or projects beyond the wall surface into the room instead of being "flat mounted" as is the usual type of grille.

One object of the invention is to provide an extended grille which, unlike a flat grille, has room within the grille to accommodate volume control damper blades.

Another object of the invention is to provide a grille which includes grille bars or blades that serve as deflector or diffuser blades, the blades being formed of sheet metal and bendable at the time of installation to various required angles for securing a desirable lateral air distribution pattern from the grille.

A further object is to provide a grille which supports the volume control dampers and also supports stack head turning vanes so that the grille, damper blades and turning vanes constitute a unitary structure that provides for the desired vertical and lateral distribution of the air and for control of the volume of air through the register in relation to other registers in an air delivery system either of the hot air type or for cooling purposes, the structure being particularly adapted for forced circulation so that the duct area may be at a minimum and preferably small enough to pass through ordinary walls between the studding of the wall.

Still a further object is to provide a grille having an extended frontal design wherein the diffuser blades are arranged in a substantially convex pattern with relation to the wall, thereby eliminating reduction in area for air passage through the diffuser blades as in the usual flat type of grille and furthermore permitting such angularity of the diffuser blades particularly at the sides of the grille for the purpose of deflecting a portion of the air stream so that it will leave the grille substantially parallel to the wall surface in which the grille is mounted.

With these and other objects in view, my invention consists in the construction, arrangement and combination of the various parts of my grille whereby the objects contemplated are attained, as hereinafter more fully set forth, pointed out in my claim, and illustrated in the accompanying drawings, wherein:

Fig. 1 is a plan view of a grille embodying my

2

invention and showing it mounted on a wall, the wall being shown in section.

Fig. 2 is a front elevation of the grille with portions broken away to conserve space.

5 Fig. 3 is a sectional view on the line 3—3 of Fig. 2 showing the diffuser blades in the right half of the grille set at a different angle than those in the left half of the grille whereby a non-symmetrical lateral air distribution pattern is had.

10 Fig. 4 is a sectional view on the line 4—4 of Fig. 2 showing the grille and volume control dampers supported thereby in relation to a duct end.

15 Fig. 5 is a diagrammatic view similar to Fig. 4 showing the addition of turning vanes to the grille and damper blades, thereby providing a complete register.

20 Fig. 6 is a plan view on a reduced scale showing a non-symmetrical lateral air distribution pattern resulting from the adjustment of the diffuser blades to the positions of Fig. 3 and showing by dotted lines a symmetrical pattern.

25 Fig. 7 is a similar plan view showing a symmetrical pattern in which a diffusion pattern is provided for discharge into the end of a long room instead of into the side of a narrow room or hall as in Fig. 6.

30 On the accompanying drawings I have used the reference character W to indicate a wall and G my grille mounted on the wall. The grille G comprises a sheet metal stamping having a peripheral frame comprising upper and lower horizontal members 10 and 12 and vertical members 14. Upper and lower flanges 16 and 18 extend forwardly or into the room as shown in Figs. 1 to 3 and between the flanges 16 and 18 diffuser blades 20 are mounted. These may be suitably secured to the flanges 16 and 18 and are preferably formed of sheet metal so that they can be bent to various angles, those in the right half of Fig. 3, for instance, being different than those in the left half.

35 The grille G also includes upper and lower flanges 22 and 24 secured to the flanges 16 and 18 and adapted to support damper blades D by means of hinge connections 26 along their rear edges. The damper blades D are adapted to be opened as in Fig. 4 or closed as shown by dotted 40 lines when air through the grille is undesirable.

Suitable linkage may be provided for this purpose, but forms no part of my present invention and accordingly has not been illustrated. One form of such linkage, however, is disclosed in the copending application of Hermanson and Joesting, Serial No. 656,274 filed March 22, 1946.

The blades D are adapted to be equally opened as shown, for instance in Fig. 5, by interconnecting linkage such as that disclosed in the above mentioned copending application. In an installation of my grilles, the maximum open position of each grille is balanced by the heating or air conditioning engineer in relation to all other grilles in the system. Thus the desired air flow for each room supplied by the system is assured.

In connection with the grille and damper combination, I provide turning vanes V (see Fig. 5) which are curved sheet metal blades supported at one or both ends by one or a pair of brackets 23. The brackets 23 are suitably secured to the side flanges 30 which connect the ends of the upper and lower flanges 22 and 24 together. Thus the assembly of grille, damper blades, and turning vanes is a unitary structure and mounted as such in the wall W by means of the simple expedient of two screws 32 as shown in Fig. 3.

This simplifies the installation of the grille, damper, and vane combination which may be termed a "register" inasmuch as only a single unit need be mounted in the duct after the duct has been installed and the walls plastered. The duct is shown at 34 and has a right angle bend or stack head indicated at 36 in which the turning vanes V are located.

The diffuser blades 20 being bendable, as already mentioned, may be adjusted at the time of installation as to the positions shown in Fig. 3 when it is desirable to get wide lateral air distribution from the right half of the grille as in Fig. 6 and less diffusion from the left half. This is particularly adaptable for a room having a wall 38 closer to the grille than the opposite wall so that a non-symmetrical diffusion pattern 39 is had or in the case of a long narrow hall having a wall 40, the blades 20 in the left half may be adjusted similar to those in the right half for securing lateral diffusion in both directions and a symmetrical pattern as shown by the dotted lines 42.

On the other hand in a narrow room where the grille is mounted at the end of the room and the walls 44 and 46 are relatively close together, the desirable pattern may be as indicated at 48 in Fig. 7 and in that case the blades 20 in both halves of the grille would be positioned at the angles shown in the left half of Fig. 3.

My grille has a number of advantages as distinguished from the flat type of prior art devices. In a flat grille the diffusion blades, when set to get some lateral air distribution, tend to reduce the discharge area, as there is actually less area through the blades because they are distributed over only the duct area whereas by extending the grille as in Fig. 3 the area over which the blades is distributed is increased.

Also the blades adjacent the sides of the grille are arranged in a curved pattern that bends toward the wall and permits of a greater number of blades for each unit of duct area, at the sides of the grille where more blades are required for lateral distribution as distinguished from only slight diffusion of the air stream adjacent the center of the grille. This permits of directing the air stream into wide angularities with less resistance to the air flow.

Adjacent the sides of the grille the blades 20 are comparable with turning vanes and can be set so as to secure wide lateral distribution as indicated by the patterns 39 and 42 in Fig. 6. The discharge area is affected only slightly and there is no appreciable increase in resistance as in the case of a flat register.

A grille and diffuser blade combination of the kind disclosed permits of wide adjustability of air stream angularities and permits controlling the air stream pattern to fit almost any room condition. It also reduces drafts in the occupied zone and yet secures a maximum of air distribution with a minimum of stratification.

The dampers D can be adjusted so that their wide open position is the maximum as in Fig. 4, or some position less than maximum as in Fig. 5 to take care of the size of the room and the air pressure at each individual grille. The dampers thus permit balancing of the air flow and temperature from each grille in relation to every other grille in the system and eliminate the necessity of volume dampers in the basement. My arrangement also simplifies installation and adjustment and thereby effects a saving due to reduction of installation labor.

The turning vane arrangement reduces air resistance and gains maximum efficiency at the stack head. The vanes also provide for maximum efficiency in vertical air distribution from the register. They also permit sharp turns in the duct work whereas the installation of a duct in an ordinary wall does not permit slow turns due to space limitations.

The grille G may be used alone or in combination with the vanes V. The grille can also be used with or without the volume control dampers D and constitutes a register when the dampers are used. The entire unit is thereby adaptable for various types of installations by using all the three parts (the grille, the dampers, and the turning vanes) or the grille alone or the grille with the dampers or with the turning vanes.

Some changes may be made in the construction and arrangement of the parts of my grille without departing from the real spirit and purpose of my invention, and it is my intention to cover by my claim any modified forms of structure or use of mechanical equivalents which may be reasonably included within the scope.

I claim as my invention:

A register comprising a peripheral frame portion adapted to be attached to a wall, upper and lower horizontally disposed flanges connected to and extending outwardly from said frame portion, said flanges having an outline convex in shape with respect to said frame portion, a plurality of relatively narrow and adjustable diffuser blades vertically arranged between the outer edges of said upper and lower flanges, said flanges and blades thus forming a convex grille, upper and lower horizontally disposed flanges attached to said grille and extending rearwardly beyond said wall attachment frame portion, vertically disposed flanges connecting said horizontally disposed rearwardly extending flanges, a pair of upper and lower horizontally disposed damper blades each having a rear edge pivotally attached to a rearmost portion of one of said rearwardly extending flanges, said blades extending forward from the pivotal attachments sufficiently to extend into the space outlined by said convex grille when they are in their open position, and turning vanes attached to brackets arranged behind

5

said damper blades, said brackets being attached to said vertically disposed flanges.

JOHN E. PETERSON.
